UNITED STATES PATENT OFFICE.

OLIVER E. GOODELL, OF BANGOR, MICHIGAN.

PLOW-CARRIAGE.

SPECIFICATION forming part of Letters Patent No. 237,010, dated January 25, 1881.

Application filed April 1, 1879.

To all whom it may concern:

Be it known that I, OLIVER E. GOODELL, of Bangor, in the county of Van Buren and State of Michigan, have invented an Improvement in Plow-Carriages, of which the following is a specification.

The nature of this invention relates to certain new and useful improvements in the construction of carriages for supporting and operating plows.

The invention consists in the peculiar construction, arrangement, and combination of certain devices for regulating the pitch of the plow, all as more fully hereinafter set forth.

15 In the drawings, Figure 1 is a perspective view. Fig. 2 is an enlarged perspective of the device for raising and lowering the wheels.

In the accompanying drawings, which form a part of this specification, A represents a suitable frame, in the downwardly-projecting ends of which are journaled the crank-shafts or axles B B, which carry the traction-wheels C.

D is a supplemental frame connected to the frame A by means of the bent arms E.

25 F are ratchet-bars securing the two frames A D together at their tops, and with which engage the levers G, the lower ends of which are secured to a ratchet-faced block, H, which engages with a similar block, I, secured to the 30 crank-shaft, as shown, and by means of which the said shafts are raised or lowered by the operation of the levers G. By securing the levers to ratchet-blocks their position in relation to the cranks can be changed, and they 35 can be adjusted to move the cranks more or less in either direction, as desired.

The tongue P is removably secured in the

frames, as shown. An L-iron or rod, R, is vertically adjustably secured to the side of the tongue by means of an eyebolt and washer, c, and serves as a stop to prevent the point of the plow from flying out of the ground upon coming to an obstruction.

J is an adjustable bail, one end of which is pivoted in the frame A by a bolt, a, which 45 passes through both bars of the frame and the bail, while the opposite end passes through the opposite side of the frame, being pivoted in the same at b, and terminating in an arm, K.

The short arm of a bell-crank lever, L, pivoted upon the side of the tongue, is pivoted to the free end of the arm K by a link, N, and by these means the plow, which is secured to the bail by means of a clamp, O, as shown, is raised or lowered, as may be desired.

55 The bail, arranged as shown in the accompanying drawings, is adjusted for the operation of a right-hand plow, and in order to operate a left-hand plow the bail should be reversed and the tongue shifted to the left. By 60 this construction the lever which operates the parts last described is always between the horses, and avoids injury to the latter should they fly back.

What I claim as my invention is—

65 In a plow-carriage, the bail J, reversibly secured within the frame A, substantially as described, in combination with the lever L, arm K, and link N, as and for the purposes set forth and shown.

OLIVER E. GOODELL.
